MACHINE FOR OPERATING UPON HIDES,
SKINS, AND LEATHERCutler D. Knowlton, Rockport, and David Edgar,
Lynn, Mass., assignors to United Shoe Machinery Corporation, Flemington, N. J., a corporation of New Jersey

Application September 9, 1942, Serial No. 457,734

19 Claims. (Cl. 69—41)

This invention relates to machines for operating upon hides, skins, and leather. While the invention is illustrated as embodied in a machine for performing glazing operations upon tanned hides and skins, it is to be understood that in various novel and useful aspects the invention is not limited to use in machines of the illustrated type.

It has heretofore been proposed to provide two rotary tools rotating in opposite directions with respect to each other to treat all portions of a given work piece upon one passage through the machine in an arrangement in which work feeding means is provided to feed said work piece continuously in one direction to secure treatment thereof. In one machine of this type, operation of the work treating rolls or cylinders is controlled by a feed roll located between the work treating cylinders. Since the cylinders rotate at relatively high speed as compared with the rate of feed of the work piece, it is quite possible for the rear end of the work piece to be snatched from the feeding roll as the end of the work piece is being approached, particularly in the case of skins of very irregular contour and having one or more projections or tabs which maintain the feed roll in its raised position when but little of the skin is in position to be gripped by said feed roll to maintain the skin against the pull of the work treating cylinder. Under the conditions described, the end portions of skins are apt to be damaged, particularly where the work treating tools are bladed cylinders. In another type of machine employing two work treating cylinders, means is provided separate from the feed rolls for controlling the time of operation of the work treating cylinders, said work controlling means being commonly in the form of a feeler device at the exit end of the machine, the result being that the machine will take care of only those work pieces of a quite substantial length dimension.

It is an object of this invention to provide a multiple cylinder work treating machine capable of treating work pieces of sheet material having a wide range of length dimensions and to provide further a machine which will feed or present to treating tools work pieces which are extended and therefore not subject to damage even if of the most irregular contour.

It is an important feature of the invention that detector, feeler or other work controlled devices are provided at both the entrance and exit ends of the machine for controlling the work treating rolls or cylinders in such manner that the cyl-

inders operate in succession on the work piece and always while the work piece is firmly held by the work feeding means, whereby the work piece is properly tensioned during treatment by the cylinders and maintained against displacement, thus obviating any possibility of damage as in certain prior constructions.

In the illustrated construction, work feeding rolls are positioned at the entrance and exit ends 10 of the machine and serve also as feeler devices to control the time of operation of the work treating cylinders. Conveniently, work supporting means is provided individual to each work treating cylinder and movable to press the work piece 15 against the cylinder, the timing of the movements of the work supports determining the sequence of operations of the work treating cylinders. As shown, the work supports are operated by individual fluid operated means under control of 20 solenoids in electrical circuits which are opened and closed in suitably timed relation to each other by connections to feeler devices disposed in the path of the work pieces.

25 These and other important features of the invention and novel combinations of parts will now be described in detail in the specification and then pointed out more particularly in the appended claims.

30 In the drawings,

Fig. 1 is a view in side elevation, and partly in section, of a glazing machine illustrating one embodiment of the invention; and

35 Figs. 2 to 5, inclusive, are more or less diagrammatic views illustrating positions of the work treating elements at various points in the progress of a work piece through the machine.

In the illustrated machine, which is designed 40 particularly for glazing operations upon hides and skins, there is provided an endless work supporting belt or conveyor member 8 passing around relatively large rolls 10 and 12, the roll 12 being preferably driven by power means to progress the work pieces, such as that shown at 13, through 45 the machine at a rate of about 60 feet per minute. The other roll 10 is rotatably supported in the upper ends of a pair of arms 14 pivotally supported on the machine frame, springs, one of which is shown at 16, being provided to keep the 50 conveyor belt 8 under driving tension and to permit portions of the belt to be moved upwardly into work presenting position with respect to one or the other of two work treating rolls, devices or cylinders 18 and 20. Obviously, additional 55 work treating rolls or devices may be incorporated

in the machine without departing from the principles of the invention.

For cooperating with the conveyor belt 8 in feeding a work piece during treatment thereof there is provided a pair of final feed rolls 22, 24 of which the lower feed roll 24 serves also as a support for the conveyor belt 8 where it is pressed upon by the upper feed roll 22 which engages the work piece as the latter is presented thereto during the travel of the said belt 8. Since however both of the rolls 22 and 24 are power driven they serve as positive work feeding means along with the belt 8.

For driving the conveyor 8 and the feed rolls 22, 24 there is conveniently provided an electric motor indicated at 26 to which is coupled a shaft 27 having fixedly secured thereto a relatively small pulley 28 about which passes a belt 30 which also passes about a larger pulley 32 secured to a shaft 34 having fixedly secured thereto the belt supporting and driving roll 12. Also secured to the shaft 34 is a pulley 36 about which passes a belt 38 engaging with a much smaller pulley 40 secured to the shaft of the feed roll 24, the pulleys 32, 36 and 40 being so proportioned as to drive the feed roll 24 at a peripheral speed corresponding to the travel of the conveyor belt 8. As shown the feed rolls 22, 24 are geared together by gears 41 and 43 having teeth sufficiently long to maintain the gears in mesh while separated additionally by the thickness of the work piece.

There is also provided an initial or first pair of feed rolls 42, 44 for engaging the upper and lower surfaces of the conveyor belt 8 at the entrance end of the machine, intermeshing gears being provided for driving the upper feed roll 42 from the lower feed roll 44, these feed rolls being driven at the same speed as the feed rolls 22 and 24 by reason of a belt 46 which engages at its opposite ends with pulleys of the same size as the pulley 40 which, as before stated, is driven at a speed to provide for proper cooperation of the feed rolls with the conveyor belt 8.

As shown, each of the upper rolls 22 and 42 is mounted at its ends in vertically slideable blocks one of which is shown at 50 and another at 52 (Fig. 1), the said blocks being held yieldingly in their lowermost positions by means of springs 54 so that said feed rolls 22 and 42 may readily be accommodated to variations in the thickness of the work piece undergoing treatment. Conveniently, the upper feed rolls 22 and 42 are made to serve also as feeler devices since they are raised by the entering end of the work piece and dropped again as the work piece passes away therefrom. To this end the feed roll 42, when lifted by the entering end of the work piece closes a switch at 60, the feed roll 22 also serving as a feeler through operation of a pivoted lever 62, since upward movement of that end of the lever above the feed roll 22 results in closing a switch at 64 and opening another switch at 66. In this connection, it is noted that blocks 61, 63 and 65 house mercury switches at 60, 64 and 66, respectively, which are closed upon pressure on a switch member 67, 68 and 69, respectively.

The work treating rolls or cylinders 18 and 20 are driven at very much higher speed than the travel of the conveyor belt 8, power means for driving the rolls being conveniently provided by a belt 70 passing around a relatively large pulley 72 on the shaft which carries the pulley 28, the said belt 70 also engaging a relatively small pulley 74 on a shaft 76 supported in the frame of

the machine, said shaft also carrying a much larger pulley 78 about which passes a belt 80 engaging at its other end with a small pulley 82 secured to the shaft of the work treating cylinder 20 to drive the latter in a clockwise direction and at relatively high speed. Also secured to the shaft 76 is a gear 84 in mesh with a gear 86 of the same size on a shaft 88 journaled in the machine frame and having secured thereto a pulley of the same size as pulley 78 and having engaged therewith a belt 90 which passes around a pulley 92 of the same size as pulley 82 to drive the work treating roll 18 at the same speed as the roll 20 but in the opposite direction. Since both of the work treating rolls 18 and 20 are relatively heavy rolls and driven at high speed, they are mounted, as shown, in journals stationary on the machine frame.

To render the work treating rolls 18 and 20 operative, the work piece must be presented thereto, this being conveniently accomplished by pressing the work piece against the periphery of one or the other of the rolls by lifting the conveyor belt toward the work treating roll while the latter is rotating. As shown, there is a work support or presser member individual to each of the two work treating rolls 18 and 20, the said work support comprising a bed roll 100 or 102 mounted for free rotation at its opposite ends in power operated members 104 responsive to control by the feed rolls 22 and 42 acting as feeler devices, as will hereinafter be more fully described.

Since each of the power operated members 104 is similar in all respects to each of the other three and is similarly operated, a description of one will apply to all four. By reference to Fig. 1 it will be seen that each member 104 projects from one end of a cylinder 106 and has its other end secured to a piston 108 which is slideable in the cylinder 106 and is operated by pressure of fluid against it. The pressure fluid, preferably oil, is admitted into the cylinder 106 through a pipe 110 to which is connected a branch pipe 112 opening into a valve cylinder 113 in which slides a vertically movable valve member 116 having a portion 118 of reduced diameter. When the valve member 116 is moved upwardly to bring the reduced portion 118 opposite to the end of the pipe 112 the pressure fluid flows from a pipe 120 to the pipe 112 and thence by pipe 110 to the lower end of cylinder 106. As shown, the lower end of the piston 108 has a cup-shaped depression 109 to facilitate entrance of the fluid under pressure into the space between the lower end of the piston 108 and the bottom of the piston cylinder 106. It will be understood that the two members 104 at opposite ends of the bed roll 100 are lifted at the same time to press the adjacent portion of the conveyor belt 8 toward the work treating roll 18. Similarly the two members 104 associated with the bed roll 102 are lifted simultaneously to carry the said roll 102 upwardly to press a work piece on the conveyor belt against the work treating roll 20.

Conveniently the means for forcing the fluid under pressure into the cylinders 106 comprises a rotary pump 130 arranged to be driven by a belt 132 from a pulley 134 on the motor driven shaft 27, said belt 132 passing around a pulley 136 on the shaft of the rotary pump. Extending from the pump casing is the pipe 120 which is provided at an intermediate point with a relief valve 140 which is adjustable in a well-known manner, by turning the hand wheel 142 to vary

the pressure of the operating fluid, excess fluid escaping from the valve through an exhaust pipe 142 into a sump or reservoir 144. It will be understood that, when each pair of valves 116 is moved upwardly to connect the two associated cylinders 106 with the corresponding pipes 120, the pressure fluid enters the cylinders 106 and causes upward movement of the bed roll 100 or 102. Upon reverse movement of the valves 116 to the position shown in Fig. 1, a reduced portion 148 of each valve will be located opposite to the lower end of each pipe 110 so that the fluid under pressure in the cylinders 106 may drain into the sump 144 through the pipes 150.

For operating the valves 116, each valve is provided with connections to its individual solenoid 160 or 161 in a suitable electrical circuit arranged to be controlled by one or both of the feeler devices represented by feed rolls 42 and 22. When the solenoids 160 or 161 are energized, their associated valve members 116 are lifted to bring the reduced portions 148 opposite to the ends of the pipes 112 and 120 so that pressure medium flows to the corresponding cylinders 106. At the same time the openings connecting the pipes 110 with the pipes 150 are closed since the reduced portions 148 of the valves 116 have been moved upwardly to a position such that a full-diameter portion of the valve 116 covers the openings of the pipes 110 and 150 into the valve cylinders 113. When the solenoids 160 or 161 are deenergized, springs 162 at the lower end of the valve members 116 move the latter downwardly to restore the reduced portions 148 to their fluid releasing position with respect to the pipes 110, the result being that the bed roll 100 or 102 is lowered, thus terminating the operation of the associated work treating roll 18 or 20.

When a work piece such as that shown at 13 is placed upon the conveyor belt 8 at the entrance end of the machine, it is progressively carried along until its forward end lifts the upper feed roll 42, upward movement of the roll 42 serving to close the switch at 60 (Fig. 1) with the result that the solenoids at 160 are energized to move the valve members 116 upwardly to a position such that the pressure medium is directed through the pipes 110 to the corresponding cylinders 106 at opposite ends of the bed roll 100. The upward movement of the pistons 108 and of the bed roll 100 results in pressing the adjacent portion of the conveyor belt upwardly toward the work treating roll 18, the arrangement being such that the belt just touches the periphery of such work treating roll. Hence, when the advance edge of the work piece moves in to the field of the work treating roll 18 it is contacted with substantial pressure to effect a glazing operation. Since the bed roll 100 is lifted by hydraulic means, which must about half fill the cylinder 106, the upward movement of the bed roll is not instantaneous but takes place promptly enough so that it is in position when the forward end of the work piece reaches a vertical plane connecting the axes of the roll 18 and of the bed roll 100. Hence, the work treating roll 18 operates upon all of the advance portion of the work piece, as shown in Fig. 3. When, however, the forward end of the work piece 13 lifts the work feeding roll 22, the latter acting as a feeler device closes the switch at 64 thus energizing the solenoids 161 and at the same time opens the switch at 66 thus deenergizing the solenoids at 160, the result being that bed roll 102 is lifted to press the work piece against the work

treating roll 20 while at the same time the bed roll 100 is depressed to terminate the operation of the work treating roll 18, all as indicated in Fig. 4. It follows that part of the work piece treated by the work treating roll 18 is also treated by the work treating roll 20 to insure that no portion of the work piece is missed in the passage of the latter through the machine. When the work piece 13 progresses far enough for the work feeding roll 42 to drop off of the rear end of the work piece, there is no change in the relative positions or in the operation of the work treating rolls 18 and 20. This is made clear by Fig. 5 wherein it will be seen that the work treating roll 20 continues to operate on the work piece and work treating roll 18 remains inoperative as in Fig. 4. Furthermore, from Fig. 5 it will be clear that the work feeding rolls 22 and 24 maintain control of the work piece until the work treating roll 20 has completed its treatment and that there is no possibility of the work treating roll 20 displacing the work piece at any time since during its whole operation the work piece is under control of the work feeding rolls 22, 24. When the work piece moves far enough to permit the roll 22 to drop into contact with the conveyor belt 8, the contact points of the switch at 64 are separated thus deenergizing the solenoids at 161 with the result that the bed roll 102 drops away from the work treating cylinder 20 thus rendering the latter inoperative as shown in Figs. 1 and 2.

Having described our invention, what we claim as new and desire to secure by Letters Patent of the United States is:

- 35 1. In a machine for operating upon hides, skins, and leather, work supporting means, means for feeding a spread out work piece through the machine, a pair of cylinders located above the work supporting means and operative to treat a work piece thereon, a feeler at the entrance end of the machine adapted to be engaged by the entering end of the work piece, means controlled by said feeler to cause operation of the work treating cylinder adjacent the entrance end of the machine, a feeler at the exit end of the machine, and means controlled by the last-mentioned feeler upon entrance of the work piece below the latter to initiate operation of the work treating cylinder nearer to the exit end of the machine, whereby said work treating cylinders operate in succession and in timed relation to each other as determined by said feelers.
- 40 2. A machine constructed according to claim 1 in which the work supporting means includes work supporting members located one below each work treating cylinder to support the work piece during operation of the associated work treating cylinder, means for moving each work supporting member toward and from its associated work treating tool to present the work piece to the tool for treatment thereby and to move the work piece out of engagement with the tool, and electrical means including switches for initiating operation of said moving means, said switches being controlled by the feelers to secure successive operation of said work treating cylinders.
- 45 3. A machine for operating upon hides, skins, and leather, means including an endless work supporting belt for feeding a work piece, a pair of cylinders located above the belt and operative to treat a work piece thereon, a feeler at the entrance end of the machine adapted to
- 50
- 55
- 60
- 65
- 70
- 75

be engaged by the entering end of the work piece, means controlled by said feeler to cause operation of the work treating cylinder adjacent the entrance end of the machine, a feeler at the exit end of the machine, and means controlled by the last-mentioned feeler upon entrance of the work piece below the latter to initiate operation of the work treating cylinder nearer to the exit end of the machine, whereby said work treating cylinders operate in succession and in timed relation to each other as determined by said feelers.

4. A machine constructed according to claim 3 in which a switch is provided in an electrical circuit to be controlled by the feeler at the exit end of the machine to terminate operation of the work treating cylinder at the entrance end of the machine at about the same time that the work treating cylinder at the exit end of the machine becomes operative to treat the work piece.

5. A machine constructed according to claim 3 in which work supporting members are provided one below each work treating cylinder to press the belt and the work piece thereon against the associated work treating cylinder, fluid operated means for moving each work supporting member toward and from its associated work treating cylinder to present the work piece to the cylinder for treatment thereby and to move the work piece out of engagement with the cylinder, and electrical means including switches for initiating operation of said fluid operated means, said switches being controlled individually by the feelers to secure successive operations of said work treating cylinders.

6. In a machine for operating upon hides, skins, and leather, a first feed roll at the entrance end of the machine, work supporting means with which said first feed roll cooperates in feeding a work piece through the machine, a work treating cylinder adjacent to said first work feeding roll and rotating in the same direction as said first feed roll, a final feed roll cooperating with said work supporting means at the exit end of the machine, a work treating cylinder adjacent to and preceding the final feed roll and arranged to rotate in a direction the reverse of said final feed roll, both feed rolls being movable upwardly upon entrance of a work piece between the individual feed roll and the work supporting means, and switches in electrical circuits to control the operation of said work treating cylinders, one of the switches being closed upon upward movement of the first feed roll to initiate operation of the work treating cylinder adjacent to said feed roll, and another of said switches being closed by the final feed roll to initiate operation of the work treating cylinder adjacent thereto, whereby said work treating cylinders operate in succession to effect treatment of the work piece.

7. A machine constructed according to claim 6 in which still another switch is provided and arranged to be controlled by the feed roll at the exit end of the machine to terminate operation of the work treating cylinder at the entrance end of the machine at about the same time that the work treating cylinder at the exit end of the machine becomes operative to treat the work piece.

8. In a machine for operating upon hides, skins, and leather, a pair of cylinders rotating in opposite directions to treat a work piece, a conveyor belt to present a work piece to the

cylinders, a feed roll at the entering end of the machine, a similar feed roll at the exit end of the machine, a member below each work treating cylinder operative to support and press the belt and a work piece thereon against its associated cylinder, fluid operated means for operating said members, means controlled by the feed roll at the entrance end of the machine to initiate upward movement of the work supporting member associated with the cylinder adjacent to the entrance end of the machine, and means controlled by the feed roll at the exit end of the machine to initiate upward movement of the work supporting member associated with the other work treating cylinder upon entrance of the work piece below said last-mentioned feed roll.

9. In a machine for operating upon hides, skins, and leather, a pair of cylinders rotating in opposite directions to treat a work piece, a conveyor belt to present a work piece to the cylinders, a pair of feed rolls at the entering end of the machine, one above and one below the conveyor belt, a similar pair of feeding rolls at the exit end of the machine, a member below each work treating cylinder operative to support and press the belt and a work piece thereon against its associated cylinder, fluid operated means for operating said members, means controlled by the feed rolls at the entrance end of the machine to initiate operation of said fluid operated means to effect upward movement of the work supporting member associated with the cylinder adjacent to the entrance end of the machine, and means controlled by the feed rolls at the exit end of the machine to initiate operation of the fluid operated means to effect upward movement of the work supporting member associated with the other work treating cylinder upon entrance of the work piece between said last-mentioned feed rolls.

10. In a machine for operating upon hides, skins, and leather, a pair of cylinders rotating in opposite directions to treat a work piece, a conveyor belt to present a work piece to the cylinders, means for supporting and driving said belt, a feed roll at the entering end of the machine, a similar feed roll at the exit end of the machine, a member below each work treating cylinder operative to press the belt and a work piece thereon against its associated cylinder, fluid operated means for operating said members, means controlled by the feed roll at the entrance end of the machine to initiate upward movement of the work supporting member associated with the cylinder adjacent to the entrance end of the machine, and means controlled by the feed roll at the exit end of the machine to initiate upward movement of the work supporting member associated with the other work treating cylinder, said last-mentioned feed roll also having connections to control the first-mentioned work supporting member to cause depression of the latter at about the same time that the other work supporting member is lifted into cooperative relation with respect to its associated work treating cylinder at the exit end of the machine.

11. In a machine for operating upon hides, skins, and leather, a pair of cylinders rotating in opposite directions to treat a work piece, a conveyor belt to present a work piece to the cylinders, a pair of feed rolls at the entering end of the machine, one above and one below the conveyor belt, a similar pair of feeding rolls

at the exit end, a member below each work treating cylinder operative to press the belt and a work piece thereon against its associated cylinder, fluid operated means for operating said members, means controlled by the feed rolls at the entrance end of the machine to initiate upward movement of the work supporting member associated with the cylinder adjacent to the entrance end of the machine, and means controlled by the feed rolls at the exit end of the machine to initiate upward movement of the other work treating cylinder upon entrance of the work piece between said last-mentioned feed rolls, said last-mentioned feed rolls also having connections to control the first-mentioned work supporting member to cause depression of the latter at about the same time that the other work supporting member is lifted into cooperative relation with respect to its associated work treating cylinder at the exit end of the machine.

12. In a machine for operating upon hides, skins, and leather, a pair of work treating cylinders, rotatable in opposite directions to treat a work piece, means for moving a work piece along continuously in one direction for treatment by said cylinders, a feed roll at the entrance end of the machine, a similar feed roll at the exit end of the machine, a work supporting member below each work treating cylinder, fluid operated means for each work support to move the latter upwardly to press a work piece against its associated work treating cylinder, solenoids each in an electrical circuit for initiating operation of each fluid operated means, and switches in the electrical circuits for controlling said solenoids, one of the switches being controlled by the work feeding roll at the entrance end of the machine to initiate upward movement of the work support associated with the work treating cylinder at the entrance end of the machine when the work piece lifts the adjacent feed roll, and another of said switches being controlled by the work feeding roll at the exit end of the machine to initiate operation of the work supporting member associated with the work treating cylinder at the exit end of the machine when the forward end of the work piece lifts the last-mentioned feed roll, whereby said cylinders become operative in succession to treat the work piece.

13. A machine constructed according to claim 12 in which still another switch is provided for control by the feed roll at the exit end of the machine to initiate depression of the work support associated with the work treating cylinder at the entrance end of the machine, whereby the work treating cylinder at the entrance end of the machine is rendered inoperative at about the same time that the work treating cylinder nearer the exit end of the machine is rendered operative by upward movement of the work supporting member.

14. In a machine for treating pieces of sheet material, work supporting means, means for feeding and extending a work piece over the supporting means, work treating tools located above the work supporting means, a first detector at the entrance end of the machine adapted to be operated by the entering end of the work piece, means controlled by the said first detector to bring the first portion of the said work piece into en-

gagement with a work treating tool, a second detector at the exit end of the machine adapted to be operated by the work piece, and means controlled by the said second detector to bring the last portion of the said work piece into engagement with a work treating tool.

15. In a machine for treating pieces of sheet material, work supporting means, means for feeding and extending a work piece over the supporting means, work treating tools located above the work supporting means, a first detector at the entrance end of the machine adapted to be operated by a work piece when being fed into the machine, a final detector at the exit end of the machine adapted to be operated by the work piece when being discharged from the machine, means for yieldably holding a first portion of the work piece and one of said tools in engagement, said holding means being under the control of the first detector, and means for yieldably holding a second portion of the work piece and another of said tools in engagement, said latter means being under the control of the final detector.

16. A machine constructed according to claim 14 in which the second detector is provided with additional means whereby engagement of the first portion of the work piece with a tool is terminated at about the same time that the last portion of the work piece is engaged by a tool.

17. In a machine for treating pieces of sheet material such as hides, skins or leather, work supporting means, a conveyor belt with associated feeding rolls for feeding and extending a work piece over the supporting means and passing it through the machine, work treating tools located above the work supporting means, a first detector at the entrance end of the machine adapted to be operated by the entering end of the work piece, means controlled by the said first detector to bring the first portion of the said work piece into engagement with a work treating tool, a second detector at the exit end of the machine adapted to be operated by the work piece, and means controlled by the said second detector to bring the last portion of the said work piece into engagement with a work treating tool.

18. A machine constructed according to claim 14 in which the operative relationship of the two detectors to the tools is such that the said last portion of the work piece overlaps the said first portion of the work piece.

19. In a machine for treating pieces of sheet material, work supporting means, a first set of feeding rolls for introducing a work piece over the work supporting means, a second set of rolls for discharging the work piece from the machine, work treating tools spaced along the path of movement of the work piece and between the two sets of rolls, said tools being adapted to bring forces in opposite directions to bear on the work piece and along said path of movement, detector means arranged above the said work supporting means to be operated by the passage of the work piece, and means controlled by the said detector means to bring the tools selectively into engagement with the work piece such that the work piece, while being treated, is always under tension because of a pull between one set of rolls and a tool.
